F. F. BEALL.

GEAR.

APPLICATION FILED APR. 29, 1918.

1,360,358.

Patented Nov. 30, 1920.

By Inventor,
Frank F. Beall,
Milton Tibbets, Atty.

UNITED STATES PATENT OFFICE.

FRANK F. BEALL, OF DETROIT, MICHIGAN, ASSIGNOR TO PACKARD MOTOR CAR COMPANY, OF DETROIT, MICHIGAN, A CORPORATION OF MICHIGAN.

GEAR.

1,360,358.

Specification of Letters Patent. Patented Nov. 30, 1920.

Original application filed December 23, 1914, Serial No. 878,733. Divided and this application filed April 29, 1918. Serial No. 231,422.

To all whom it may concern:

Be it known that I, FRANK F. BEALL, a citizen of the United States, and resident of Detroit, Wayne county, State of Michigan, 5 have invented certain new and useful Improvements in Gears, of which the following is a specification.

This application is a division of application Serial No. 878,733 filed December 23, 10 1914.

This invention relates to gears and gear manufacture and particularly to gears formed by pressing or forging as distinguished from cutting or casting.

15 One object of this invention is to provide gears having teeth denser at and adjacent the faces than elsewhere.

Another object of this invention is to provide gears having teeth the faces of which 20 are compressed and die finished and the tops of which have a cut finish.

Other objects of the invention will appear from the following description, taken in connection with the drawings which form a 25 part of the specification and in which:—

Figure 1 is a part elevation and part section of a gear blank in the form in which it leaves the drop hammer;

Fig. 2 is a similar view of the blank after 30 leaving the roughing die;

Fig. 3 is a similar view of the blank after leaving the finishing die and before the excess metal has been removed;

Fig. 4 is a similar view of the finished 35 gear;

Fig. 5 is a plan view of half of a finished gear like that shown in Fig. 4;

Fig. 6 is a fragmentary enlarged end elevation of several of the teeth of the finished 40 gear showing in dotted lines the contours of the teeth in various stages of completion; and

Fig. 7 is an enlarged sectional view of the finished gear showing in dotted lines the 45 contours of a tooth in various stages of completion.

This invention involves die pressing a blank to form teeth by displacing the metal of the blank with space forming die parts so that metal extends beyond the normal 50 limits, as the tops, for instance, of the teeth, and then removing the excess, as by grinding or machining. The blank may be so

supported that some excess metal will be pressed outwardly at the ends of the teeth, 55 and this excess metal may likewise be removed.

The invention also involves die pressing a blank having teeth of abnormal proportions so that the teeth are pressed into the desired 60 shape. As illustrated herein, a blank having teeth of abnormal thickness is die pressed so that the sides of the teeth are compressed to the desired face contour. The abnormally thick teeth may be formed by forging or die 65 pressing with a roughing die.

In the form of the invention particularly set forth herein, a gear blank having a plain face is drop forged, is then placed in a die press where a roughing die forms teeth of 70 abnormal thickness and preferably of less height than the required finished tooth, is then subjected to a second die pressing operation in which a finishing die compresses the thick teeth to the desired contour and forces 75 excess metal outwardly beyond the normal tops and perhaps at the ends of the teeth, and is then machined or ground to remove the excess metal. The last step is the hardening of the finished gear. Gears made by 80 this method will be found in most cases to be accurate enough for the finest work, but if desired a finishing cut may be made on the faces of the teeth before hardening to give a still greater degree of accuracy. 85

A gear made in accordance with the above referred to method is shown herein and comprises teeth the faces of which are compressed and die finished leaving the metal denser at and adjacent said faces, and the 90 tops and ends of which have a cut finish where the excess metal has been removed either by machining or grinding.

Referring to the drawings, B represents generally a gear blank and in Fig. 1 it is 95 a plain blank 30 having a web portion 31 and a portion 32 in which the gear teeth are to be formed. In Fig. 2 the blank B is shown as having teeth 33 which are thick relative to the spaces between them and not 100 as high as the teeth of the finished gear should be. As shown the teeth and spaces have no sharp corners it thereby being possible to form such a blank either by a quick rough pressing process or by drop forging. 105 As shown also, the teeth are arranged in a

generally diagonal direction and are curved lengthwise, but other desired forms of teeth may be made.

In Fig. 3 the gear blank B is shown as having its teeth 33 formed with correct faces 34 but an excess of metal extends above the normal tops of the teeth as shown at 35, the dotted lines 35' representing the normal top of one of the teeth. Some of the excess metal has also been pressed outwardly at the ends of the teeth as at 36 and 37. Aside from the excess metal above referred to, the teeth of the gear shown in Fig. 3 are perfectly formed and would be ready for use. In Figs. 4 and 5 the gear blank B has become a finished gear 38, the excess metal above referred to having been entirely removed either by machining or grinding, thus leaving a cut finish at the tops and on the ends of the teeth. In Figs. 6 and 7 enlarged views of gear teeth are shown, 35, 36 and 37 representing in dotted lines the excess metal that has been removed, and these views illustrate the clean sharp edges that are obtained by thus pressing the teeth and subsequently removing the excess metal. In these figures also the dotted line 39 traces an outline of the tooth 33 of the gear shown in Fig. 2 as it comes from the roughing die.

Ordinarily the gear thus completed will be

sufficiently accurate for use, but if desired a machining or grinding process may be carried out on the faces of the teeth before it is case hardened. Case hardening gives the desired wearing qualities to the faces of the teeth and is particularly efficient when combined with the compressing of the gear teeth as herein described.

It will be understood that the invention is not limited to the specific gear herein shown and described, but is capable of modification in various ways without departing from the scope of the claims.

Having thus described my invention, what I claim and desire to secure by Letters Patent is:—

1. A metal gear having teeth of denser formation at and adjacent the side faces than on the top surfaces thereof.
2. A metal gear having teeth of denser formation at and adjacent the side faces than on the top and end surfaces thereof.
3. A metal gear having teeth, the faces of which have a die finish and the top surfaces of which have a cut finish.
4. A metal gear having teeth, the faces of which have a die finish and the tops and ends of which have a cut finish.

In testimony whereof I affix my signature.

FRANK F. BEALL.
